UNIVERSAL SUPPORT FOR CURTAINS
AND THE LIKE

Rudolph Murn, Lakewood, Ohio

Application March 19, 1945, Serial No. 583,469

4 Claims. (Cl. 248—259)

1

Customarily, curtain rods are supported by brackets which are fastened to the woodwork of window framing by screws or short nails. If the mounting has to be changed on account of wider or narrower curtains for instance, the brackets have to be removed and be replaced. This defaces the woodwork. It is also time-consuming. In the present invention, however, a construction is had which is quickly and easily attached and detached, and without damage to the woodwork. Other objects and advantages will appear from the following description.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a front elevational view showing an embodiment of the invention as mounted on the upper part of a window frame;

Fig. 2 is a front elevation on large scale showing a detail of the clamping means, as in open position;

Fig. 3 is a similar view with the clamping means closed in final position;

Figs. 4 and 5 are sectional views taken on planes indicated substantially by lines IV—IV and V—V respectively, Fig. 3;

Fig. 6 is a vertical sectional view taken on the plane indicated substantially by line VI—VI, Fig. 3; and

Fig. 7 is an analogous view showing a slight modification.

The rod R for carrying curtains, drapes and the like, is supported by two clamping means C, Fig. 1, as clamped in place on convenient portions of the woodwork or trim of window framing and the like. Conveniently, the rod R may be of telescoping extension form, and having its in-bent ends 2, Fig. 6, slidably engageable on brackets 3 which may be of generally known or desired form. The bracket 3 is secured to a clamping plate 4 by suitable means. The clamping plate also carries a clamping jaw 5, preferably adjustable along the plate, as for example by a slot 6 in the plate, and a screw 7 therethrough into the clamping jaw or a spacer member 8 secured thereto. The head 9 of the screw 7 is tightened down so as to hold the jaw 5 at the position desired on the plate 4. Adjustably slid-

2

able on the end of the plate beyond the jaw 5 is a clamping hook member 10. One convenient way of slidably mounting this member is by in-bending its edges 11 such as to engage around the edges of the plate 4 and be slidable therewith. The free end of the member 10 has downturned slight projections 12 capable of firmly holding when in clamped position.

For the manipulation of the clamp, that is, expanding or drawing together the clamping member 10 and the clamping jaw 5, a toggle lever 13 is pivoted at 14 to the plate 4, and a link 15 is pivoted at 16 to the lever and at 17 to the clamping member 10. As the pivot point 16 is beyond the lever pivot 14 when in closed position, a toggle locking means is had, and when the end of the lever 13 is swung around into the closed position shown in Fig. 3, it rides over and snaps into locked position beyond the head 9 of the screw 7. A thumb or push lug 18 facilitates the manipulation of the lever 13.

To set up the equipment, the clamping means C, with its jaws separated by the lever 13 being swung into open position as in Fig. 2, is placed at the location desired on the window trim or the like, and the lever 13 is swung around into locking position, as in Fig. 3, by its push lug 18. The other clamping means C is similarly positioned and locked for the other end of the curtain rod, and the latter, extended to corresponding length, is slipped into position with its in-turned ends 2 over the brackets 3. Conversely, if desired, the rod R may be assembled with the brackets 3, and the clamping means C at each end may then be set onto the framing or trim and the toggle levers 13 may be swung down into closed or clamping position.

By reason of the form of the clamping means, including the hook clamping member 10 and the clamping jaw 5, and additionally an in-turned lower end 20 of the plate 4, trims and contours of widely varying shape may be engaged between the jaws 12 and the jaws 5 or the jaws 20 engaging under the lower edge of the framing member 10 if in such large form. By slightly modifying the shape of the hook clamping member 10, such as to the rounded or curved form 10', Fig. 7, accurate clamping over moldings, as well as very irregular forms of trims and framing, may be attained. The clamping mechanism otherwise, including the clamping jaw, plate, lever, etc., and the curtain bracket, is the same as afore-described.

The particularly easy and quick removal and replacing of the clamping or support means

greatly facilitates cleaning of woodwork, framing, etc., and the bodily removal or relocating of curtains, draperies and the like. And withal, the device is of simple construction and low cost in production.

Other modes of applying the principle of the invention may be employed, change being made as regards the detail described, provided the features stated in any of the following claims, or the equivalent of such, be employed.

I therefore particularly point out and distinctly claim as my invention:

1. In means for supporting curtains and the like, a clamp plate, a relatively movable clamping jaw adjustably secured on said plate by a slot in the plate and a screw extending through the slot to the jaw, a hook clamping member slidable on said plate by in-turned margins engaging over the plate edges, a toggle lever pivoted to said plate, a link connected to the hook clamping member and to a point on said lever beyond its pivot point, and a push lug on the free end of the toggle lever, the lever being aligned to lock over the head of the aforesaid screw.

2. In means for supporting curtains and the like, a bracket adapted to be secured to the framing of a wall opening, means for clamping the bracket to a narrow portion of trim protruding on the upper zone of the face of said framing and also gripping under the lower edge of the framing, including a clamp plate, a relatively movable clamping jaw adjustably secured on said plate by a slot in the plate and a screw extending through the slot to the jaw, a hook clamping

member slidable on said plate, a toggle lever pivoted to said plate, and a link connected to the hook clamping member and to a point on said lever beyond its pivot point.

5. In means for supporting curtains and the like, a clamp plate, cooperating clamping members on said clamp plate with a toggle connection and including three jaws, one engaging above said framing, one engaging below the framing, and one slidable on the face of the framing to engage under a narrow portion of trim protruding on the upper zone of the framing, said toggle connection extending between said plate and the jaw engaging above said framing.
